DESIGN FOR A COMBINED TOILET PAPER HOLDER AND ASH RECEIVER

James R. Smith, Sr., Trenton, N. J., assignor to New Jersey Porcelain Company, Trenton, N. J., a corporation of New Jersey

Application June 26, 1936, Serial No. 63,505

Term of patent 14 years

To whom it may concern:

Be it known that I, James R. Smith, Sr., a citizen of the United States, residing at Trenton, in the county of Mercer, State of New Jersey, have invented a new, original, and ornamental Design for a Combined Toilet Paper Holder and Ash Receiver, of which the following is a specification, reference being had to the accompanying figures of the drawing, forming part thereof.

Fig. 1 is a perspective view of a combined toilet paper holder and ash receiver showing my new design;

Fig. 2 is an end view; and

Fig. 3 is a plan view of the holder shown in Fig. 1.

I claim:

The ornamental design for a combined toilet paper holder and ash receiver as shown.

JAMES R. SMITH, SR.
